No. 624,117.

W. STEPHENSON.
SEED DRILL.

Patented May 2, 1899.

(Application filed Apr. 15, 1898.)

(No Model.)

UNITED STATES PATENT OFFICE.

WILLIAM STEPHENSON, OF MORRIS, CANADA.

SEED-DRILL.

SPECIFICATION forming part of Letters Patent No. 624,117, dated May 2, 1899.

Application filed April 15, 1898. Serial No. 677,668. (No model.)

To all whom it may concern:

Be it known that I, WILLIAM STEPHENSON, a citizen of the Dominion of Canada, residing at Morris, in the county of Provencher, in the 5 Province of Manitoba, Canada, have invented certain new and useful Improvements in Seed-Drills; and I do hereby declare that the following is a full, clear, and exact description of the construction and operation of the same.

10 My present device relates to improvements in the class of agricultural implements above named, by which, first, their draw-bars may be rendered more easy of adjustment than those as at present constructed; second, an 15 improved device for adjusting the spring tension of the side scrapers.

Hitherto it has been found very difficult to adjust the drill-shoe grain-spouts to the rubber feed-tubes with draw-bars of different 20 lengths in order to get the shoes in the desired position known as "dodged," or one in rear of the other alternately, and the first part of my invention is of such improved construction as will conveniently enable an operator 25 to adjust the shoes to draw-bars of different lengths in the field or otherwise with only a simple wrench.

My device consists, first, in forming a circular-shaped projection on the front of the 30 grain-spout (or the equivalent thereof as a standard in some machines) about three inches in diameter with a bolt-hole in the centre, and about one-third in from the outer edge of the same a circle of small corrugations 35 or notches on both sides. Two circular castings of the same diameter as the projection on the grain-spout guard have their inner sides constructed with corresponding corrugations in order to fit one on each side of the 40 said projection on the grain-spout guard. The outer sides of the said circular castings have two projections or ribs between which to form a bed to receive the ends of the draw-bars, the several parts being all adjustably held 45 together by a bolt made to pass through each and tightened by a nut, as will be further explained hereinafter.

My device consists, secondly, in the improved tension of the side scrapers, by which 50 they can be more easily and quickly adjusted, according to the conditions of the soil, to clean the disks.

Reference being made to the accompanying drawings, Figure 1 represents a side view of disk and grain-spout in an upright position. 55 Fig. 2 is a rear view of the same. Fig. 3 is a side view of the grain-spout detached from the disks. Fig. 4 is a side view of the end of one of the draw-bars. Fig. 5 is an elevation of one of the circular castings. Fig. 6 is a 60 similar but outside view. Fig. 7 is an edge view of one of the circular castings. Fig. 8 is an end view of the parts bolted together. Fig. 9 is an inside view of one of the side scrapers. Fig. 10 is a perspective view of one 65 of the side-scraper levers. Fig. 11 is a side and edge view of the top portion of the central scraper. Fig. 12 is an elevation of the lower central scraper. Fig. 13 is an edge view of the upper and lower parts of the double 70 central scraper. Fig. 14 shows grain-spout at different angles in dotted lines when draw-bars of various lengths are attached thereto and the rubber tubes bending into the top.

In the drawings, A A represent the two 75 disks, which are mounted in converging planes, as described in my prior patents, No. 588,027, dated August 10, 1887, and Nos. 603,862 and 603,863, dated May 10, 1898, on the axles of the casting B and secured thereto by the 80 notched metal caps C.

D is the circular-shaped projection cast on the forward portion of the grain-spout and having a bolt-hole e through its center and both of its sides having corrugations a around the 85 same, as shown.

E, Figs. 5 and 6, represents the circular castings which fit on each side, respectively, of the circular-shaped projection D.

b are the corrugations on the inside of each casting E, and c are projecting ribs on the outside of both of said castings E E to act as a bed for the reception of the ends of the two draw-bars f f, the same being secured by means of a bolt g, made to pass through the hole d in 95 each of the draw-bars, the hole h in each of the circular castings or washers E E, and also through the hole e of the projection D to hold the parts together and tighten them by the nut i on the threaded end of the said bolt g, 100 as shown at Fig. 8. Thus it will be seen that the corrugations b on the inner side of each of the circular castings or washers E fit the corresponding corrugations a on both sides

of the projection D of the grain-spout B, which prevents the washers E from turning after the ends of the draw-bars f f are placed on the bed of each washer E after the grain-spout 5 is adjusted as desired and the parts tightened up by the nut i on the bolt g. By this construction the disks can be set out of line with each other—that is to say, the disks of each gang can be so set as to be alternately in front 10 of and behind a medial transverse line—and the grain-spout of each disk can be so adjusted as to be vertical, or inclining backward or forward, so as to conveniently receive the ends of the rubber grain-feed tubes j (shown 15 in dotted lines) without unnecessary wear or friction against the said grain-spout B. It will further be observed that with the old plan of construction in order to set the grain-spouts dodged would necessitate the making 20 of a different draw-lug with a special angle for every length of draw-bar, while my present device can suit any length of draw-bar or angle to which to adjust the grain-spout B.

The side scrapers consist of two irregular 25 shaped plates q, provided with lugs r, secured to their inside surface, as shown at Fig. 9, to each of which is pivoted a lever s by the pin m, attached to each lever entering the said lugs r r, the said levers being provided about 30 the center with a steel pin a, affixed thereto for the purpose of pivoting said levers to lugs h, cast on each side, respectively, of the grain-spout B. Cotter-pins b, passed through the pins a, hold the levers in place. The upper 35 end of one of the levers s is bent inward, and a spiral spring t of the requisite degree of strength is slipped over the said lever end and over the right-angled point n of the opposite lever to press the upper ends of said 40 levers apart, and thus cause the said side scrapers q to impinge at the desired angle on the outer side of the disks A, as shown at Figs. 1 and 2, and clean them. The tension of the said spring t can easily be adjusted by making 45 the arm s wide enough to fill the inside of the coiled spring t and provided with two projections u u on the arm to pass between the coils of the said spring, one on each side, acting as a thread to turn the spring either on or off, the 50 other end of the spring having the last coil made smaller and oval-shaped to fit the end of the right lever, which is flat-pointed, so as not to allow the spring to turn from the position it is set to, according to the nature of the 55 soil the machine is to work in. By this means the outside cutting edge of each disk is kept clear of soil. The inner face of each of the said disks is kept clean by means of two adjustable central scrapers w and w'. The lower 60 one, w, is beveled to correspond to the slanting position of the disks, as shown at Fig. 2, and detached at Fig. 12, having a longitudinal slot x, over which a washer z is placed for a screw-bolt g' to pass through and made to screw

into the lug i on the rear of the casting grain-spout B, the upper part of the said scraper resting against the lug 3 on the said grain-spout casting. Thus it will be seen that by means of the slot x the scraper w can be adjusted vertically to suit the angle of the two 70 disks B B to keep their central portion clear of mud when in operation.

The inner edges of the disks are beveled about five-eighths of an inch from the outer edge, and the short upper portion w of the 75 scraper is beveled from its center downward to correspond to the bevel of the disks, as shown at Fig. 2. It has also a slotted opening x', through which a capped screw y is made to pass to screw into the lug i', cast on 80 the rear of the grain-spout casting B, a washer z being placed between the screw-head and the scraper. Thus the said upper scraper can be adjusted so that the wear of the same can be taken up to correspond to the bevel 85 of the disks. In their normal position the top scraper w' will overlap the lower one, w, about one-eighth of an inch, the result of 90 these two central scrapers being to keep the inside surfaces of the disks always clean as they revolve past the scrapers when in operation.

Having thus described my device and its advantages, what I claim as my invention, and desire to secure by Letters Patent, is— 95

1. The combination of a grain-spout having circular projections with corrugated faces on each side thereof, drill-disks upon the lower end of the grain-spout, draw-bars for pulling the grain-spout, and washers, each having 100 corrugated inner faces to engage the projections on the grain-spout and ribbed outer faces to receive the rear end of the corresponding draw-bar, the said grain-spout, projections thereon, washers and draw-bars having registering bolt-holes therein, and a bolt passing through the said hole to lock the parts in 105 their adjusted position.

2. The combination with drill-disks and a grain-spout, of pivoted arms each of which 110 carries a scraper for a disk on one end thereof, one of the said scraper-arms having its opposite end bent inwardly, and provided with projections, a spiral spring having its one end mounted upon the said inwardly-bent end of 115 the scraper-arm, and engaging the projections thereon, and having its opposite end contracted in one direction, and a similar-shaped projection on the free end of the opposite arm, whereby the spring may be held against turning; substantially as described.

Dated at Hamilton, Ontario, this 7th day of March, 1898.

WM. STEPHENSON.

In presence of—
WM. BRUCE,
WM. SMITH.
